J. Baxendale.

Calico Printing.

No 10719.

Patented Mar. 28. 1854

UNITED STATES PATENT OFFICE.

JAMES BAXENDALE, OF FALL RIVER, MASSACHUSETTS, ASSIGNOR TO J. BAXENDALE AND JAS. FERGUSON.

METHOD OF OPERATING THE DOCTORS OF CALICO-PRINTING CYLINDERS.

Specification of Letters Patent No. 10,719, dated March 28, 1854.

To all whom it may concern:

Be it known that I, JAMES BAXENDALE, of Fall River, in the county of Bristol and State of Massachusetts, have invented a new 5 and useful Method or Contrivance for Operating the Doctors of Calico-Printing Cylinders, which invention may be denominated an "Irregular Traverse-Motion;" and I do hereby declare that the same is 10 fully described and represented in the following specification and the accompanying drawings, letters, figures, and references thereof.

Of the said drawings Figure 1, denotes 15 an end view of the said invention. Fig. 2, a vertical and central section of it, taken in line of its axis. Fig. 3, is a view of the arrangement, of its pinion and eccentric gears.

20 The object of my invention is to produce an irregular traverse motion of the doctor of a calico printing cylinder, in order to prevent the usual injury to the engraved surface that results from the usual regular 25 traverse movements thereof. As the doctor is moved with a reciprocating motion constantly between and up to two given points or bounds, there is shortly produced, an injurious wear on the engraved surface, of the 30 printing cylinder, the nature of which is well known to calico printers. My invention not only causes the doctor to be moved with a reciprocating motion, but it continually effects a change in the extent there- 35 of, so that the doctor when moving in either direction never is arrested or brought to a stop at precisely the same spot or place where it was brought up to a stop during its next preceding movement.

40 Having thus stated the purpose of my invention I shall now proceed to explain its nature and operation.

In the drawings, A B, represent two metallic plates or disks placed at a suitable 45 distance asunder, and connected by three or any other suitable number of cross bolts or bars, c, c, &c., which are to be so made and applied as to keep the plates apart and hold them in place. The rear plate or disk, is to 50 be affixed on the axle of the blanket roller or that of some other roller of the calico printing machine to which a regular rotary motion is imparted during the working of the said machine. The said axle is to pass 55 centrally through the plate, A, and be fas-

tened to it so as to cause the plate to be revolved with and by it when it is put in revolution.

On three stationary journals or pins D, E, F, projecting inward from the inner surface of the plate B, and fastened to such plate, three spur gears G, H, I, are made to revolve. The centers of their journals are arranged respectively in the vertices of an equilateral triangle, and they are each 60 placed a like distance eccentrically to the centers of the gear wheels. Fig. 4, is a diagram which serves to exhibit the disposition of the journals with respect to the centers of the wheels. In this figure, a, b, and c, 65 may be supposed to exhibit the respective centers or axes of the wheels, G, H, I; and d, e, f, to be the centers or axes of their respective journals. The centers of the journals are placed at the same distance, a d, b 70 e, or c f, from their centers, a, b, c, the distances, a d, b e, c f, being supposed to be taken on parallel lines. Between the said three gears, G, H, I, is a pinion gear, K, 75 whose teeth are made to engage with those of each of the three spur wheels. This pinion gear is fixed on a shaft, L, which extends through a hole, M, bored centrally 80 through the plate, B, larger in diameter than the shaft and sufficiently so to allow the shaft to play freely in accordance with the compound movement which is imparted to it by the eccentric gear. The shaft is 85 kept in place by two beads or strong checks, or circular heads N, O, that are respectively 90 fastened on it, and made to rest against the opposite surfaces or sides of the plate, B, as seen in the drawings.

The outer end of the connecting rod of 95 the rocker shaft of the doctor or set of doctors is to be firmly fixed to the shaft, L, so that such shaft shall not revolve in such end, and so that the movements of the shaft shall be effected by the movements imparted to the pinion gear. The pinion gear therefore 100 does not revolve consequently during the rotary movements of the plates A, B. They not only cause the three eccentric gears to rotate around the pinion gear, but to rotate on their respective journals or spindles. Now as their spindles are fixed firmly in the 105 plate, B, and the latter rotates only on its center or axis, the necessary result will be that the pinion gear must have imparted to it a constantly variable reciprocating move- 110

ment, whereby such a movement will be imparted to the doctor. The movement is not only a reciprocating one, but its limits are constantly varying.

5 The common traverse motion produced by a crank or an eccentric is maintained within certain limits, which limits are constant, the doctor continually working up to and between them. But with my invention the 10 limits of reciprocating motion are constantly changed in position, and by means of such, the doctor is enabled to work on the engraved surface of the printing cylinder, without producing the injurious consequences that result from its always stopping and starting from one spot, as is the 15 case, when the motion is given by a crank or an eccentric.

The black, red, and blue circles in Fig.

4, serve to illustrate the relative positions 20 of the pitch circles of the four gears, during each third part of a revolution of one of the eccentric gears.

I claim as my invention—

A compound traverse mechanism constructed of eccentric gears, and a pinion gear and a supporting frame, substantially as described as applied for obtaining a compound traverse or constantly variable reciprocating movement of the doctor of a 30 calico printing roller.

In testimony whereof I have hereto set my signature this twentieth day of October A. D. 1853.

JAMES BAXENDALE.

Witnesses:

LOUIS LAPHAM,
ALMANZA S. LINDSEY.
